US0D1076719S

(12) **United States Design Patent** (10) Patent No.: **US D1,076,719 S**
(45) Date of Patent: ** May 27, 2025

(54) **AUTONOMOUS VEHICLE**

(71) Applicant: **Applied Electric Vehicles Ltd., Scoresby (AU)**

(72) Inventor: **Luciano Nakamura, Scoresby (AU)**

(73) Assignee: **Applied Electric Vehicles Ltd., Scoresby (AU)**

(**) Term: **15 Years**

(21) Appl. No.: **29/877,071**

(22) Filed: **Jun. 1, 2023**

(30) **Foreign Application Priority Data**

Dec. 2, 2022 (AU) 202217176

(51) **LOC (15) Cl.** **12-08**

(52) **U.S. Cl.**

USPC **D12/86**

(58) **Field of Classification Search**

USPC D12/16, 86, 88, 90-92; D21/433-434, D21/533, 535; 296/181.1-181.5, 183.1

CPC B62D 25/00; B62D 25/06; B62D 33/00; B62D 35/00
